UNITED STATES PATENT OFFICE.

ALBERT GARBCZ, OF EAST HAMMOND, INDIANA, ASSIGNOR OF ONE-HALF TO W. H. NEWBURG, OF MEDFORD, WISCONSIN.

WRENCH.

Application filed May 11, 1922. Serial No. 560,067.

To all whom it may concern:

Be it known that I, ALBERT GARBCZ, a citizen of Poland, residing at East Hammond, in the county of Lake and State of Indiana, have invented certain new and useful Improvements in Wrenches, of which the following is a specification.

This invention relates to certain new and useful improvements in wrenches and has particular reference to the provision of an improved form of sliding adjustment wrench wherein the inner jaw is slidably mounted upon the rigid shank of an outer jaw.

An object of the invention is to provide efficient means for obtaining quick adjustment of the inner sliding jaw and for maintaining such jaw in its adjusted position.

Another object is to generally simplify an improved sliding jaw wrench whereby the same may meet with all of the requirements for a successful commercial use.

Still another object of the invention is to provide a removable and reversible double slidable inner jaw with means for maintaining the same in adjusted position upon the shank of a rigid outer jaw when either face of the inner jaw is presented to the surface of the outer jaw.

With the above general objects in view and others that will appear as the nature of the invention is better understood, the same consists in the novel construction, combination and arrangement of the parts herein-after more fully described, illustrated in the accompanying drawings, and pointed out in the appended claim.

In the drawings forming a part of this application and in which like designating characters refer to corresponding parts throughout the several views:

Figure 1 is a view partly in section and partly in side elevation of a wrench constructed in accordance with the present invention.

Figure 2 is a front elevational view of the wrench shown in Figure 1.

Figure 3 is a sectional view taken on line III-III of Figure 1.

Figure 4 is a view similar to Figure 3 taken on line IV-IV of Figure 1.

Figure 5 is a fragmentary view showing the outer end of the shank in elevation and its rigid jaw in longitudinal section,

Figure 6 is a sectional view taken in two planes as represented by section lines VI-VI 55 of Figure 1.

Figure 7 is a developed elevational view of the latch for holding the outer jaw against turning movement on the shank, and

Figure 8 is a detail sectional view on line 60 VIII-VIII of Figure 5 showing the screw pin entering the slot in the reduced end of the shank for swivelly connecting the outer jaw thereto.

Referring more in detail to the several views, the present invention embodies, a symmetrical shank 5 preferably constructed of bar iron and having a reduced cylindrical portion 6 at its outer end onto which is revolubly fitted a rigid outer jaw 7 having 70 a single operating face 8, the jaw 7 being provided with a socket for snug reception of the reduced portion 6 as shown clearly in Figure 5. The reduced portion 6 of the shank is provided with an annular groove as 75 at 9 and a screw 10 is threaded transversely of the jaw 7 so that the inner ends of said screw engage in the groove 9 so as to removably fasten the jaw 7 upon the reduced portion 6 of the shank. The opposite side 80 of the jaw 7 is provided with a recess 11 opening into the socket in which the reduced portions 6 is fitted, and this socket is covered by a suitable plate 12 fastened in place by screws 13 or the like, the plate 12 85 being preferably of inwardly dish form for a purpose which will presently become apparent.

The recess 11 is reduced at its inner portion so as to provide a shoulder against 90 which is seated a washer 14 through which is slidably disposed a small latch bolt 15 which also extends through the plate 12, and a helical spring 16 is provided between the washer 14 and pivot plate 12 surrounding 95 the latch bolt 15 so as to normally urge the latter into a suitable socket 17 provided in one side of the reduced portion 6 of the shank 5, the washer 14 being suitably fastened to the latch bolt 15 so as to move with the latter. By dishing the cover plate 12, the latch bolt 15 may lie normally flush with or inwardly of the adjacent side face of the jaw 7 so as to not be damaged accidentally and yet the latch bolt 15 is readily accessible 100 for being withdrawn whenever it is desired.

to revolve the jaw 7 so as to overlie the other one of the two jaw faces 18 of a double face inner sliding jaw 19 which is snugly slidably fitted upon the shank 5. The opposite side of the reduced portion 6 is provided with a similar socket 17 so that the jaw 7 may be maintained in either position. By means of this construction the latch bolt 15 may be frail in nature as the same merely acts to prevent rotation of the jaw 7 while the greatest strain is upon the screw 10 which is utilized to hold the jaw 7 on the reduced portion 6.

The shank 5 is provided with a series of uniformly spaced sockets 20 in each edge thereof, and one socket in each edge is adapted to be engaged by means of a pin 21 fixed to the outer end of an adjacent pivoted lever 22, one lever 22 being pivoted between suitable ears 23 at each edge of the jaw 19 upon a pivot pin 24 as clearly shown in Figures 1 and 4. The pins 21 slidably extend through suitable openings in the edges of the jaw 19 so that they may engage in the sockets 20, and for convenience in manipulation as well as to permit making of the structure as little cumbersome as possible, the levers 22 are disposed at an oblique angle to the longitudinal axis of the shank 5 so as to lie with their inner ends in a plane to one side of said axis of the shank 5 as seen in Figure 2. In other words, this permits the inner ends of the levers 22 to move inwardly toward each other past the edges of the shank 5 when the levers 22 are swung to disengage the pins 21 thereof from the socket 20.

A spiral compression spring 25 is disposed between and suitably connected to the inner ends of the levers 22 so as to normally separate these ends for yieldingly maintaining the pins 21 normally in the socket 20 of the shank 5, and it will be seen that by means of a double latching arrangement of this kind a very effective maintenance of the inner jaw in adjusted position is had.

In operation, the jaw 19 may be released by pressing together the inner ends of the levers 22 so as to release the pins 21 from

the sockets 20 and while grasping the levers 22, the operator may force the jaw 19 toward or from the jaw 7 as desired. The levers 22 may then be released and the spring 25 will automatically swing the same so as to engage the pins 21 in the adjacent sockets 20, thus effectively securing the inner jaw 19 against movement on the shank. Should one of the faces 18 of the jaw 19 become damaged, the other may be employed by releasing the latch bolt 15 through an outward pull thereon, and then the jaw 7 may be revolved on the reduced portion 6 of the shank for a half revolution until the jaw 7 is disposed with its face 8 overlying the outer jaw face 18. The latch bolt 15 is then released to engage the adjacent socket 17 and said jaw 7 is thus effectively maintained in the position to which it has been brought. This construction is also desirable should the jaw 19 have two faces of different forms for operating upon different types of work, as is obvious.

From the foregoing description, it is believed that the construction and operation as well as the advantages of the present invention will be readily understood and appreciated by those skilled in the art.

Minor changes may be made without departing from the spirit and scope of the invention as hereinafter claimed.

Having thus described the invention, what I claim as new is:—

A sliding adjustment wrench including a shank having the outer end thereof reduced in cylindrical form, an outer jaw having a socket in which the reduced portion of the shank is snugly revolvably fitted, means carried by said jaw and engaging the reduced portion of the shank to prevent detachment of the jaw from the latter while permitting the revolution of the jaw on said reduced portion, and means to hold the jaw against rotation on said reduced portion when said jaw is positioned to extend from either edge of said shank, and a sliding inner jaw having opposed working faces to selectively cooperate with the revolvable outer jaw.

In testimony whereof I affix my signature.
ALBERT GARBACZ.
